UNITED STATES PATENT OFFICE

153,655

DESIGN FOR A CABINET FOR A HEATER
OR THE LIKE

Lawrence H. Wilson, Detroit, Mich., assignor to
Motor Wheel Corporation, Lansing, Mich., a
corporation of Michigan

Application February 17, 1948, Serial No. 144,555

Term of patent 7 years

(Cl. D81—19)

To all whom it may concern:

Be it known that I, Lawrence H. Wilson, a citizen of the United States, residing at Detroit, in the county of Wayne and State of Michigan, have invented a new, original, and ornamental Design for a Cabinet for a Heater or the like, of which the following is a specification, reference being made to the accompanying drawing, forming part thereof.

The figure is a perspective view of a cabinet for a heater or the like, showing my new design.

The side of the cabinet not shown is substantially the same as the side shown and the back of the cabinet is plain.

The dominant features of my design reside in the portions shown in full lines.

I claim:

The ornamental design for a cabinet for a heater or the like, substantially as shown and described.

LAWRENCE H. WILSON.
